BOOSTER PLATE

Jesse E. Bartholomew, St. Johns, Mich.

Application January 4, 1954, Serial No. 28,354

Term of patent 14 years

(Cl. D14—6)

To all whom it may concern:

Be it known that I, Jesse E. Bartholomew, a citizen of the United States of America, residing at 505 South Oakland Street, city of Saint Johns, county of Clinton, State of Michigan, have invented a new, original, and ornamental Design for a Booster Plate, of which the following is a specification, reference being had to the accompanying drawing, forming a part hereof.

Figure 1 is a face view of a booster plate embodying my new design, and

Figure 2 is an edge view thereof.

The dominant feature of my design resides in the full line portion of the drawing.

I claim:

The ornamental design for a booster plate, as shown and described.
